CLAIM

The ornamental design for a plant stand with pot, as shown and described.

DESCRIPTION

FIG. 1 is a first perspective view of a plant stand with pot showing a new design;

FIG. 2 is another perspective view thereof;

FIG. 3 is a front elevation view thereof;

FIG. 4 is a rear elevation view thereof;

FIG. 5 is a left elevation view thereof;

FIG. 6 is a right elevation view thereof;

FIG. 7 is a top plan view thereof;

FIG. 8 is a bottom plan view thereof;

FIG. 9 is an enlarged view of portion 9 in FIG. 1;

FIG. 10 is an enlarged view of portion 10 in FIG. 1;

FIG. 11 is an enlarged view of portion 11 in FIG. 2;

FIG. 12 is a bottom perspective view, shown with environmental subject matter;

FIG. 13 is another bottom perspective view, shown with environmental subject matter; and,

FIG. 14 is a bottom perspective exploded view.

The long dash-short dash broken lines indicate cutoff boundaries for enlarged detail portion views and form no part of the claimed design. The broken line showing of wheels in FIG. 12 and legs in FIG. 13 is for the purpose of illustrating environmental subject matter and forms no part of the claimed design. The portions of the plant stand with pot shown in broken lines forms no part of the claimed design.

1 Claim, 14 Drawing Sheets
